UNITED STATES PATENT OFFICE.

JOHN F. MEIGS AND SIGARD A. S. HAMMAR, OF SOUTH BETHLEHEM, PENNSYLVANIA, ASSIGNORS TO THE BETHLEHEM STEEL COMPANY, OF SOUTH BETHLEHEM, PENNSYLVANIA.

FIRING MECHANISM FOR BREECH-LOADING GUNS.

SPECIFICATION forming part of Letters Patent No. 755,514, dated March 22, 1904.

Application filed February 2, 1901. Serial No. 45,756. (No model.)

To all whom it may concern:

Be it known that we, JOHN F. MEIGS and SIGARD A. S. HAMMAR, of South Bethlehem, in the county of Northampton, and in the State of Pennsylvania, have invented certain new and useful Improvements in Firing Mechanism for Breech-Loading Guns; and we do hereby declare that the following is a full, clear, and exact description thereof, reference being

had to the accompanying drawings, in which —

Figure 1 is a top plan view of the breech end of a gun embodying our invention; Fig. 2, an end elevation thereof; Fig. 3, a horizontal section on the line *— — —* of Fig. 2; Fig. 4, a detail view in perspective of the breech-block; Fig. 5, a like view of one member of the electric circuit opening and closing device operated by the breech-block; Fig. 6, a detail view in section of the firing mechanism; Fig. 7, a detail view in perspective of the primer-extractor; and Fig. 8 a horizontal section of the breech end of a gun having a different construction of opening and closing mechanism.

Letters of like name and kind refer to like parts in each of the figures.

The object of our invention is to provide improved firing mechanism for breech-loading guns; and to this end said invention consists in the mechanism having the features of construction substantially as hereinafter specified.

In the embodiment of our invention selected for illustration the gun body or barrel A is supported in a sleeve B, which, as usual, forms a part of the stationary or non-recoiling mount, and in which the barrel is free to reciprocate longitudinally in recoil and counter-recoil, a suitable recoil-controlling mechanism being provided, which need not be described, as it is not claimed herein. The breech-block C, which, as shown, is of conical form and provided with full or continuous thread, has a shank or stem *c* on its rear end by which it is journaled and supported in a bearing in a swinging bracket or carrier D, hinged to the gun by a vertical pin or bolt E. Meshing with a segmental series of gear-teeth *c'* on the stem *c* is a rack-bar F, that extends crosswise of the

gun in guideways in the bracket D and is connected by a link G with a curved crank-arm H 50 on the lower end of the hinge pin or bolt E. The crank-arm H is attached to a pinion-segment I, mounted on the hinge-pin, with which meshes a rack-bar K, by the reciprocation of which the pinion-segment is actuated and the 55 breech-block revolved and its bracket or carrier swung. As the means for reciprocating the rack-bar K form no part of the invention claimed herein, they need not be described.

Electricity is employed for firing the gun, 60 the firing being under the control of a manually-operated circuit-closing device L. To avoid accidental or premature firing, there are several safety devices for preventing the fire of the gun until the breech is closed, each in 65 the form of an automatically-operated circuit opening and closing device. One of said safety devices comprises a contact M, that operates with an electric primer N, of usual construction, placed in the rear end of the 70 mushroom stem O. Said contact M is in the form of a pin or bolt that is slidably mounted in a block P and adapted under the pressure of a spring to bear yieldingly at one end against the end of the primer and at its other end is connected with a wire or conductor Q. The block P is slidably mounted in guides *r* and *r* on the rear face of a collar R, swiveled on the protruding end of the stem O, and it is pivotally connected at one end to a crank-arm S on the 80 breech-block bracket or carrier D and operated, as hereinafter described, to oscillate and reciprocate the block P to move the contact M into and out of contact with the primer. The cap or collar R is conveniently swiveled to the 85 mushroom stem by forming in the latter an annular groove *o* to receive a ring T of slightly greater diameter than the end of the stem on which the cap is screwed. Said ring is made in halves to enable it to be placed in the annular 90 groove *o*. The pivotal connection between the block P and the crank S is formed by a pin U, passing through the block and having its inner end engaging a circular recess or socket *s* in the crank S, into which said end is yieldingly pressed and held by means of a 95

coiled spring V, encircling the pin and bearing at one end against the end of an enlargement of the pin-hole and bearing at its other end against a plunger W, also around the pin 5 in said enlargement, which plunger engages a collar or annular flange u on the pin. It will be apparent that by the just-described connection between the block and the crank the block and firing devices connected therewith 10 are free to move with the mushroom stem when the latter moves longitudinally from the effect of firing the gun and that no strain from this source will fall upon the crank-arm S. Upon the outer end of the pin U is a handle or knob u', by means of which the pin 15 may be drawn out of engagement with the socket of the arm S, so as to free the block P from the latter and permit it to be moved in its guides on the cap R independently of 20 the crank-arm to give access to the primer.

The arm S has a round portion or hub s', that is journaled in an opening in the bracket D, and fixedly secured to the inner end of said hub is a collar X. A pin or bolt Y, passing 25 through the arm and screwed into the collar at one end and having nuts screwed on its other end, the thread at the two ends being reversed, fastens the collar and arm together, and thus secures the arm to the bracket D. 30 On the collar Y are two spur-teeth y and y', that are not in alignment either in an axial or circumferential direction, one of which coöperates with a notch c² of a size just to receive it in the periphery of the shank or stem c of 35 the breech-block C and the other coöperates with a circumferentially-extending groove or channel c³ in said shank or stem. By the meshing or engagement of the tooth y with its notch c² when the block is revolved to open 40 the breech the arm S is turned or swung on its pivot until the tooth passes out of the notch, and then by the engagement of the tooth with the periphery of the stem or shank c the arm is held in the position to which it is 45 moved. The other tooth y' is moved into the groove c³, and thus does not interfere with the rotation of the arm. When the block is revolved in the reverse direction to close the breech, as soon as the notch c² comes again 50 opposite its tooth y one end of the groove c³ engages its coöperating tooth y', and the arm is swung back to its former position. It will be seen that by the described movements of the arm S the block P will be slid in its guides 55 in the cap R and rocked by reason of the swivelled connection of the latter with the stem O, and thus either withdraw the contact M from contact with the primer and expose the latter to permit its removal and the substitution of 60 another or place the contact M in electrical contact with the primer.

By reason of the relative position of the primer and the two pivot-pins U and Y when the breech is closed and the contact M touches 65 the primer great power is applied to the

block P by the arm S during the first portion of the movement of the latter to retract the block to uncover the primer, and we make use of this circumstance to automatically extract the primer. For this purpose we pivot 70 to the inner face of the block P a bar Z, having a wedge-form cam z on its side adapted to act on the flange of the primer as the block P slides, and thus force out the primer. The extractor Z is pivoted on an axis parallel with 75 the breech-block axis and is normally pressed by a spring A' to position to engage the primer. The extractor is in the form of a pivoted bar to enable it to be swung out of the path of the primer-seat to enable the placing of a new primer therein, and it has a notch or cavity z² in its under side, into which the flange of the newly-inserted primer enters, when the extractor is permitted to drop. Of course when the block P is slid to firing position the extractor passes off the primer-flange and its edge falls behind the latter to place the cam in position to engage said flange. The free end of the extractor Z is prolonged 80 to constitute a handle for lifting the extractor. 85

The wire Q, which is connected at one end to the contact M, is at its other end connected to a similar contact B', carried by a radial extension or prolongation of the crank-arm S and having the form of a spring-pressed bolt or pin, which by the swinging of the crank-arm is moved into and out of contact with one end of a bolt or pin C', mounted in the breech-block bracket or carrier D, the other end of which coöperates 90 with an electrode D', fixed to the gun, and which by the swinging of the carrier D is movable into and out of contact with said electrode. The pin or bolt C' is yieldingly pressed toward the electrode D' by a coiled 95 spring E'.

It will be seen that the firing-circuit is automatically opened and closed at the breech at three points by the breech opening and closing mechanism, the circuit at two of such 100 points being closed only when the breech-block is screwed into place and the other point being closed when the carrier is swung to breech-closing position. Possibility of accidental firing before the closing of the breech 105 is thus practically eliminated.

In Fig. 8 is shown a different form of mechanism for opening and closing the circuit at the primer. In this instance the contact M is carried by the arm S, being mounted in a 110 sleeve F', slidably mounted in an opening in the arm and yieldingly pressed forward by a spring G', placed between a flange or head f on the front end of the sleeve and a shoulder in the arm-opening. Forward movement 115 is limited by the head of a screw H' in the rear end of the sleeve, which abuts against the rear side of the arm S. The spring G' takes up or cushions the jar or shock from the rearward movement of the stem O when 120 125 130

the gun is fired, and thus prevents possibility of damage to the arm S and its parts from this source. The inner or forward side of the arm S reaches beyond the front end of the contact M and the sleeve F', and it is therefore necessary to slot the arm S sufficiently to permit it to pass the primer. The outer end of the sleeve F' is rounded off to prevent the sleeve catching on the fixed contact as the arm is moved to circuit-closing position.

To guard against the possibility of firing the gun before it is fully returned to place in battery, provision is made for opening the circuit and continuing it open when the gun is out of such position. This simply requires the providing of contacts I' and K', respectively, on the recoiling and non-recoiling parts of the gun structure, which only touch when counter-recoil is completed and the gun is in proper place for firing. This expedient also avoids the necessity of providing a portion of conductor between the fixed and movable parts of the structure capable of elongation and contraction. One of said contacts is mounted so that it may be withdrawn to prevent it being touched by the other, so that should there be occasion for inspection of the breech mechanism when closed, as when there has been a misfire, such inspection could be made with perfect freedom from danger of firing, which might exist should the circuit remain closed. As shown, the electrode L is secured to a bar M', slidably mounted in a groove in the cradle or non-recoiling part of the gun, being held in position by a thumbscrew N' to enable said electrode to be readily placed in and out of operative position.

It will be seen that if the man whose business it is to fire the gun keeps the manually-operated circuit-closing device in circuit-closing position the gun will be fired by the closing of the breech, and by thus operating the gun rapidly of fire is secured, and by firing at the instant the gun is aimed rapidly and accuracy of fire are obtained.

It is of course to be understood that though we illustrate and describe our improvements in some detail we do not thereby restrict ourselves to constructions embodying such details, as changes in construction may be made which will involve no departure from the scope of our invention.

Having thus described our invention, what we claim is--

55. 1. In combination with the breech-block of a gun, a firing mechanism having a movable member, connections between said member and the block, whereby said member derives motion from the block, and means whereby said member may be moved independently of the breech-block, substantially as and for the purpose described.

2. In combination with the breech-block of a gun, a firing mechanism having a movable member, connections between said member

and the breech-block whereby said member derives motion from the breech-block, said connections being separable, whereby said member may be moved independently of the breech-block, substantially as and for the purpose described. 70

3. In combination with breech mechanism, a block movable to and from firing position, an extractor carried by the block, connections whereby said block derives motion from the breech mechanism, and means whereby said member may be moved independently of the breech mechanism, substantially as and for the purpose described. 75

4. In combination with breech mechanism, a block movable to and from firing position, an extractor consisting of a bar pivoted to the block, connections whereby said block derives motion from the breech mechanism, and means whereby the block may be moved independently of the breech mechanism, substantially as and for the purpose described. 80

5. In combination with the breech mechanism of a gun, a firing mechanism, a sliding and oscillating block carrying a member of the firing mechanism, a pivoted arm, a pivotal connection between the latter and the block whereby the latter is given both its sliding and oscillating movements from the arm, and means for rocking said arm, substantially as and for the purpose described. 90

6. In combination with the breech-plug of a gun, a firing mechanism, a block carrying a member of the firing mechanism, a piece swiveled to the plug on which the block is slidably mounted, a pivoted arm, a pivotal connection between the latter and the block, and means for rocking said arm, substantially as and for the purpose described. 100

7. In combination with the rotatable breech-block of a gun, a sliding and oscillating block carrying a member of the firing mechanism for shifting the same to and from firing position, and means for moving said movable block comprising gearing that connects it with the breech-block, whereby the turning of the latter actuates said movable block, substantially as described. 105

8. In combination with the breech mechanism of a gun, an electric firing mechanism, a movable block carrying one member of a circuit opening and closing device, an arm carrying one member of another circuit opening and closing device, a connection between the block and arm whereby the block receives motion from the arm, and a connection between the arm and the breech mechanism whereby the arm receives motion from the latter, substantially as described. 115

9. In combination with the rotatable block of a breech mechanism, an electric firing mechanism, a movable block carrying one member of a circuit opening and closing device, an arm carrying one member of another circuit opening and closing device, a connection be- 120 125 130

tween the block and arm, whereby the block receives motion from the arm, and gearing between the arm and breech-block, whereby the arm receives motion from the latter, substantially as described.

10. In combination with the block of a breech mechanism, means for rotating the block, an electric firing mechanism, a circuit opening and closing device having a movable contact, an arm for moving such contact, a collar connected with the arm having teeth and a part connected to the breech-block having a notch and a circumferential groove to respectively coöperate with said teeth, substantially as and for the purpose described.

11. In combination with the rotatable block of a breech mechanism, a movable bracket or carrier therefor, an electric firing mechanism, circuit opening and closing means actuated by the rotation of the block, and circuit opening and closing means controlled by the movement of the bracket or carrier, substantially as described.

12. In combination with the block of a breech mechanism, a movable bracket or carrier therefor, an electric firing mechanism, a circuit opening and closing device comprising an arm geared to and receiving motion from the breech-block, and a circuit opening and closing means carried by the bracket or carrier, substantially as described.

13. In combination with breech mechanism, a firing mechanism, a movable part on which is mounted a member of the firing mechanism for moving said member to and from firing position, and an extractor consisting of a bar movably mounted upon and carried with said part, whereby when the latter is moved to take it from firing position, the extractor will be moved to perform its function, substantially as described.

14. In combination with breech mechanism, a firing mechanism, a sliding block on which is mounted a member of the firing mechanism,

and an extractor consisting of a bar movably mounted upon and carried by said block, substantially as described.

15. In combination with breech mechanism, a firing mechanism, a sliding block on which is mounted a member of the firing mechanism, and an extractor consisting of a bar having a wedge, pivoted to the block, substantially as described.

16. In combination with breech mechanism, an electric firing mechanism including an electrode carried by a movable block, a swinging support for the block in which the latter is slidably mounted, an arm pivoted to the block for sliding the same and a suitable support for said arm, substantially as described.

17. In combination with a breech mechanism, an electric firing mechanism, an automatic circuit opening and closing mechanism, and a safety-circuit opening and closing mechanism having an electrode in position to normally close the circuit that is movable at will to a position to open the circuit, substantially as described.

18. In a gun, the combination with a breech mechanism, an electric firing mechanism, an automatic circuit opening and closing mechanism, a safety-circuit opening and closing mechanism, comprising two electrodes, respectively on fixed and movable parts of the gun, and means whereby at will one of said electrodes may be moved to and held in position where it cannot touch the other electrode, substantially as described.

In testimony that we claim the foregoing we have hereunto set our hands this 4th day of January, A. D. 1901.

JOHN F. MEIGS.
SIGARD A. S. HAMMAR.
